REPAIR HEAD FOR HEDDLES

William H. Thorpe, Philadelphia, Pa., assignor to
Walker Manufacturing Company, Philadelphia, Pa.

Application April 6, 1950, Serial No. 154,347

4 Claims. (Cl. 139—96)

1

The object of the invention is to provide improvements in heddles broadly, but more specifically in a repair head to replace the original loop end or head of a heddle when worn and broken, without the necessity otherwise of replacing the entire heddle with its attendant shutdown of the loom, corresponding decrease in production and resultant loss in income.

Heddles, like any other piece of a fast moving mechanism, especially when characterized by reciprocatory motion, and even more so when that motion is substantially or fully vertical, frequently wear through and break particularly at some point of the end loops or eyes, and most frequently in the case of the upper loop, due to the force of gravity during each downward motion being added to the inherent inertia of the heddle, as its movement is suddenly arrested preparatory to movement in the opposite direction.

Such wear is most pronounced where the sides of the upper loop in particular are in constant engagement with the heddle-supporting bars or rods, and at least in some positions encounter any lock hooks, studs and/or slide hooks that may be present for the purpose of operatively supporting the heddle bars with respect to the upper and lower frame rails, or with respect to an auxiliary bar that is frequently interposed between the heddle bar and the neighboring rail.

Heretofore when a heddle has broken, it has been necessary to stop the loom, break the warp end, remove it from the eye of the heddle and lay it back on the beam, then separate the warp so that the unbroken end loop can be removed either by twisting or cutting, which act of itself can cause other broken ends and/or smudging or damaging the warp, then slipping the repair heddle over the heddle bars which of itself is difficult to do in the midst of a full set of threaded heddles, then re-enter the warp end through the eye of the new replacement heddle and tie the ends together, and finally adjust the warp and start the loom, an operation for which even an expert usually requires about five minutes.

By contrast, an object of the invention is to provide what may be termed and is hereinafter referred to as a lock-on repair head, the use of which in the replacement of a broken heddle involves merely stopping the loom, breaking or cutting off with pliers or cutters the broken end loop substantially at or but slightly above the exact bottom of the said loop, insert the abbreviated end into the repair head and fold over the clip and tongue thereof, thereby securing and positively locking in place the adjacent heddle

2

end, slipping the loop of the repair head over the heddle bar or rod, and starting the loom.

A further object is to provide a repair head, that essentially comprises a bar-engageable hook portion and a depending body portion having a transversely extending shoulder, from which projects an apertured clip portion, that terminates in a freely extending narrowed tongue, said clip aperture being adapted to receive the dovetailed or slightly V-shaped portion of the end of the heddle, after the loop portion proper thereof has first been removed at the bottom of said loop, and the clip portion then being bendable tightly against said heddle end, and secured in that position by bending the tongue over the shoulder of said body portion.

Still another object is to provide a repair head, that comprises a hooked portion for engagement with the usual heddle bar or rod, a body portion provided with an aperture or cutout capable of receiving the abbreviated portion of a heddle, and means to secure said heddle to said head.

With the objects thus briefly yet broadly set forth, the invention comprises further details of construction and operation, which are herein-after fully brought out in the following description, when read in conjunction with the accompanying drawings, in which Fig. 1 is an elevational view of a representative form of standard steel heddle having transversely widened loop end portions; Fig. 2 is an enlarged fragmentary upper end portion of such heddle, showing the point or level at which the loop sides are preferably removed after some part of the loop breaks; Fig. 3 shows the blank from which the improved repair head is bent; Fig. 4 is a perspective view of a repair head comprising one embodiment of the invention; Fig. 5 is a side elevational view of the same; Fig. 6 is a front elevation of the same; Fig. 7 is a vertical section on the line 1—1 of Fig. 8; and Fig. 8 is a section substantially on the line 8—8 of Fig. 7.

Referring to Figs. 1 to 8, inclusive, an ordinary well known type of heddle is shown as comprising the usual shank 1, having a substantially centrally positioned warp-passing eye 2, while its opposite upper and lower ends are provided with vertically elongated loops 3 and 4 for the reception of the usual supporting bars 5. Incidental to the act of punching out said loops, the end portions of the initial blank are widened by swaging dies or tools, that result in and leave behind them thinned areas 6, that decrease the thickness towards each other, and in surface area have a general shape that is substantially midway be-

tween a U and a V, or in other words the lateral edges of each such area converge somewhat as the sides of a V, while as they approach each other they merge into the curve of a U. The result resembles a parabolic curve, and as the formation of such swaged areas results in a displacement and flow or pushing of the metal laterally outwardly in opposite directions, the laterally opposite outside edges of the heddle adjacent thereto become divergent, dovetailed, or wedge-shaped, as indicated at 7.

During the course of ordinary use of the heddle in weaving, the sides 8 of the upper loop in particular tend to wear narrow and in time break, as hereinbefore described, and such breakage has heretofore required the removal and replacement of the entire heddle. However, the present invention merely involves the cutting off of the narrow sides of the affected loop as nearly as possible at or slightly above or below the exact base of the loop, at the level indicated by the line 9 (Figs. 1 and 2), below which a substantial portion of the divergent edges 7 are located. This divergence has been found adequate to support the major portion of the heddle by means of the repair head comprising the invention, said diverging edges in effect forming shoulders almost as positive in function as though they were in alignment and at right angles to the axis of the heddle.

Referring to Figs. 3 to 8 inclusive, one embodiment of the improved repair head is shown as when operatively positioned for the upper end of a heddle, and while it will be described as in that position, it is to be understood that it is equally adapted for use for either the upper or lower end. This repair head comprises a vertically uninterrupted side 10, from the uppermost portion of which laterally extends a reversely directed parallel hook portion 11, that terminates downwardly at 12 short of the bottom of the side 10, to provide an intervening space adapted to receive the heddle bar 5.

The lower portion of said head comprises a laterally extending bottom portion 13, that provides an upwardly terminating horizontal shoulder 14, while from the lowermost edge of said bottom portion, when bent or folded ready for use (Figs. 4, 5 and 6), there extend a pair of spaced side sections 15 and 16, connected at their free extremities by a transversely extending section 17, that together with said bottom portion and said side sections form a rectangular aperture 18, but which may be of any other suitable shape if desired, while from the lower edge of said transversely extending section 17 projects a preferably slightly tapered tongue 19. Commencing with the punched blank (Fig. 3), the lower portion of said head is initially bent into the general shape shown in Figs. 4, 5 and 6, and in this shape is preferably sold and distributed to the mills for use when needed, the shaping being done by dies that insure exact sameness of all heads sold, and resultingly exact duplication of position and functioning of all such heads when securely attached to the abbreviated end of a heddle of a given width wire.

In the case of this repair head, the broken loop end of the heddle is cut off, as before mentioned, along the line 9, and the wedge-shaped abbreviated end portion inserted upwardly through the aperture 18 in the repair head, while said heddle is axially turned substantially 45° in either direction with respect to its normal plane of operation, which is the plane of the repair head. The heddle

is then returned to its plane of normal operation and permitted to drop until its widened terminal portion 1 is restrained from further downward movement by engagement of its divergent lateral edges with the sides of said aperture 18 (Fig. 8). The side sections 15 and 16 and the transverse section 17 are then bent upwardly by pliers (or other suitable tool) into close, binding contact with the widened heddle end, and the tongue 19 similarly bent over the shoulder 14 and tightly against the rear of the bottom portion 13, thereby securing said heddle end in tight, unitary relationship with said repair head (Fig. 7). With this accomplished, the hooked end of the head 15 may be dropped over the heddle bar, if convenient to do so; otherwise, the freely extending hook terminal is temporarily deflected upwardly substantially into the position represented by the dash-and-double-dot lines 20 (Fig. 7), after which said terminal is again returned to its normal lower operative position in the plane of the opposite side 10. The heddle having been thus returned to its original position, the loom is again started and operation of the same maintained as long as desired, or until another such heddle may break, in which case it too can be provided with a repair head similar to the first and at no time disturbing the warp in the eye 2.

As an example of the approximate saving in time and increase in production, when using the new repair head over the replacement of the entire heddle as heretofore, the latter at five minutes shutdown delay on eight-pick cloth, with loom running at 184 picks per minute, amounts to 920 picks lost or 11.5 inches of cloth, whereas by the former (new) method of repair requiring about one-third the time, the loss is only 307 picks, or a gain of seven and two-thirds inches of cloths.

A further advantage resides in the fact that ordinary repair heddles are made only in nickel finish, certain wire sizes and certain eye sizes. For example, a mill using 14/80 wire, $\frac{1}{16}$ " eye, stainless wire, would have to use for repair a 14/80 wire, $\frac{1}{4}$ " eye, which is smaller, and nickel plate, which will rust. By contrast, with the new type of repair head, the same heddles are used without change in any way other than replacement of the head portion.

Having thus described my invention, what I claim and desire to protect by Letters Patent of the United States is:

1. The combination of a heddle having a dovetail end, with a repair head comprising a bar-receiving portion, a body portion having an upwardly directed shoulder, an initially depending portion having an aperture, and a tongue initially depending from said last-mentioned portion, the shank of said heddle extending through said aperture and the sides of said dovetail portion engaging the sides of said aperture to prevent escape of said end from said head, said depending portion being bent into parallelism with said body portion, and said tongue being bent reversely over said shoulder.

2. The combination of a heddle having a dovetail end, with a repair head comprising a bar-receiving portion, a body portion having an upwardly directed shoulder, and an initially depending portion, an aperture extending through said head at the joint between said body and depending portions, the shank of said heddle extending through said aperture and the sides of said dovetail portion cooperating with the sides of said aperture to prevent escape of said end

from said head, and said depending portion being bent into parallelism with said body portion.

3. The combination of a heddle having a dovetail end, with a repair head comprising a bar-receiving portion, and a depending portion having an aperture through which said heddle extends, and the sides of said dovetail portion cooperating with the sides of said aperture to prevent escape of said end from said head.

4. The combination of a heddle having a dovetail end, with a repair head comprising a bar-receiving portion, and a depending portion comprising a pair of transversely spaced portions between which said heddle extends, and the sides 15

of said dovetail portion cooperating with said spaced portions to prevent escape of said end from said head when said spaced portions are bent reversely into substantial parallelism with said depending portion.

WILLIAM H. THORPE.
